UNITED STATES PATENT OFFICE.

EBBERT J. LUND, OF JAMESTOWN, NEW YORK.

SHEET-METAL BEDSTEAD.

1,050,066.

Specification of Letters Patent.

Patented Jan. 7, 1913.

Application filed February 16, 1911. Serial No. 608,911.

To all whom it may concern:

Be it known that I, EBBERT J. LUND, a citizen of the United States, residing at Jamestown, in the county of Chautauqua and State of New York, have invented new and useful Improvements in Sheet-Metal Bedsteads, of which the following, taken in connection with the accompanying drawings, is a specification.

10 The invention relates to sheet metal furniture and the object of my improvement is to provide a sheet metal bedstead construction which is durable, cheap and when the bedstead is set up is extremely rigid; the invention consists of the construction and arrangement of the parts as shown in this specification and the accompanying drawings and pointed out in the claims.

In the drawings, Figure 1 is a perspective view of a portion of the head or foot board of a bedstead showing the corner post and a portion of the connected rail or panel portions of the same being broken away to show the construction and the panel and top rail 25 are shown in section. Fig. 2 is a lengthwise sectional view of the corner post, showing the attachment of the panel to the corner post. Fig. 3 is a detail of a portion of the edge of the panel showing the locking lugs 30 for attaching to the corner post or rails; and Fig. 4 is a perspective view of the slotted locking strip for holding the edge of the panel by means of the locking lugs; and Fig. 5 is a sectional view of the rail and the upper edge of the sheet metal panel, showing the connection of the same. Fig. 6 is a perspective view of the end and a portion of the side rail and the end of one of the bed slats in position upon the side rail. Fig. 7 40 is a perspective view of the locking strip for the lengthwise joint of the tubular side rail. Fig. 8 is a side elevation of the end of one of the bed slats.

Like numerals of reference refer to corresponding parts in the several views.

The numeral 10 designates the corner post, the tubular portion of which is preferably formed from a single sheet of metal bent into rectangular form. The lower portion 50 of the corner post 10 has cuts therein at each corner and then welded together by acetylin or electric welding so as to give the lower portions 11 of the post 10 a gradual taper.

The post 10 is formed with the slot 12 at 55 one side between the adjacent inturned edges. The edges of the sheet metal are in-turned and given a return bend in opposite

directions so as to form flanges 14 for return bend joints. A locking strip 13 is provided which engages the inturned flanges 14 each 60 side of the slot 12; locking strip 13 is so formed as to bind the parts firmly together. A lengthwise fold 15 is provided lengthwise of locking strip 13 which receives therein the edge of the panel plate 16. The plate 16 65 has the projecting spaced lugs 17 formed thereon, each having the under-cut 18 at one side. The fold 15 is provided with spaced slots 19 to receive therethrough the correspondingly spaced lugs 17.

70 It is apparent that the edge of the panel plate 16 may be inserted through the slot 12, also, that if the under-cut portions 18 of lugs 17 are on the lower side of said lugs on panel 16, then they will lock and be held in 75 slots 19 by the weight of the plate 16. The plate 16 will thus assist in holding all parts rigidly together.

The post 10 is preferably formed with a metal cap-piece 20 which is formed at its 80 lower end to enter the upper end of the sheet metal portion of the post 10. A corresponding lower end 21 is provided which enters the lower end of the sheet metal post 10, and the two cast ends 20 and 21 are connected by 85 means of a rod 22. The rod 22 preferably extends down through the block 21 for the attachment of a suitable caster to the lower end of the post 10. The cap-piece 20 is provided with a side extension 23 which fits 90 within the hollow sheet metal top rail 24 of panel 16. A cross-rod 25 is provided to connect the two corner posts of the head or foot board. The sheet metal rail 24 is attached to the upper edge of panel plate 16 the same as 95 corner post 10 is attached thereto by means of a locking strip 13. The lower edge 26 of panel 16 is preferably turned at a right angle and then bent back upon the plate 16 100 forming an acute angle therewith, thereby giving such an angular inclination to the part 26 that dust does not lodge upon the same to any extent.

Cross-rod 25 preferably extends through cap 20 into a nut 27, which nut has an opening 28 at right angles to rod 25 for rod 22 to pass therethrough, thereby locking the nut 27 firmly in position within cap 20.

105 The side rails 29 are made of hollow sheet metal by being bent from a single sheet. 110 The sides are preferably parallel except on the lower inner edge, and the edges are in-turned in opposite directions and united by a tie-strip 30 lengthwise of the lower edge

of the side rail. A strip 31 of heavy sheet metal is riveted within the ends of the tubular side rail 29; strip 31 is provided with lugs 32 which lock within correspondingly placed slots 40 in corner post 10. The strip 31 is given a rectangular bend 33 to one side in its central portion so as to brace firmly both sides of the sheet metal side rails 29. The strip 31 does not need to extend the full length of the side rail 29, but only a sufficient distance to firmly brace the sheet metal of which the side rail 29 is composed and is riveted to the opposite inner sides of the side rail.

15 The numeral 34 designates the bed slat which is preferably made with the vertical sides 35 and a flat top. The bed slats 34 are supported on side rail 29 by means of a projection 36 lengthwise of the lower edge 20 of the tubular side rail 29. Projection 36 is preferably formed on its upper side at such an angle of inclination that the dust and dirt will not accumulate on the same and is of sufficient width to allow of the 25 spaced slots 37 in said inclined upper side of extension 36. The slots 37 are spaced to correspond to the vertical sides 35 of bed slats 34. A notch 38 is provided within the vertical sides 35 and so spaced in 30 relation to the end of the slat 34 as to receive therein the vertical side of the extension 36.

It is now apparent that a tongued projection 39 is formed by the cut 38 which 35 extends within the slots 37 and the notch 38 is of just sufficient depth to permit the lower end of the tongue 39 to rest upon the inner face of the lower side of the tubular bed-slat 29. The end of the bed slat is 40 thereby braced against the upper ends of the spaced slots 37 holding the slat end firmly in position upon the tubular side rail.

I claim as new:

45 1. A sheet metal joint comprising two oppositely turned edges, a sheet metal binding strip to hold said edges, said binding strip having spaced slots therein, and a sheet of metal having spaced lugs thereon 50 corresponding to said slots to enter said slots in holding engagement.

2. A sheet metal joint comprising oppositely turned edges, a binding strip having return bend edges to engage and hold said 55 oppositely turned edges, a central lengthwise fold on said binding strip opposite the opening between the said oppositely turned edges, said fold having spaced slots therein in line with the opening between 60 said oppositely turned edges, a plate inserted in said opening and fold, an spaced lugs on said plate to engage said spaced slots.

3. In a sheet metal bedstead, a corner post comprising a sheet of metal bent in tubular form with adjacent inturned edges, a binding strip having return bend edges, said binding strip having spaced slots, a panel 65 extending between said inturned edges, said panel having spaced lugs to engage said spaced slots in said binding strip, a top rail for said panel having similar inturned edges and binding strip with spaced slots and lugs to hold said top rail on said panel, and connecting rods and caps to hold said parts together, substantially as and for the 70 purpose specified.

4. In a sheet metal bedstead, a tubular sheet metal post, a metal cap and a lower end for said sheet metal post, a rod connecting said cap and lower end, a panel attached to said corner post, a projecting shoulder on said cap, a top rail attached to said panel and fitting over said shoulder on said cap to hold the end of said rail, and a connecting rod extending through said top 85 rail and adjustably attached to said cap.

5. In a sheet metal bedstead, a sheet metal side rail comprising a sheet of metal bent in tubular form having lengthwise inturned return bend edges, a binding strip having 90 opposite return bends on its edges to hold said inturned edges firmly together, a plate riveted within the tubular end of said rail, an angular return bend in said plate to brace the sides of said tubular side rail, and 95 lugs on said plate to engage the corner post.

6. In a sheet metal bedstead, a corner post comprising a sheet of metal bent in tubular form with adjacent return bend edges, a binding strip having opposite return bend edges to engage and hold said return bend edges on said tubular post, a central lengthwise fold on said binding strip opposite the opening between said oppositely turned edges, said fold having spaced slots therein 105 in line with the opening in said oppositely turned edges, a panel plate inserted within said fold, undercut spaced lugs on said panel plate to engage in said spaced slots, a metal cap and a metal lower end for said 110 sheet metal post, a rod connecting said cap and lower end, a tubular top rail attached to said panel, and a connecting rod extending through said top rail and attached to said cap, substantially as and for the purpose specified.

In testimony whereof I have signed my name to this specification in the presence of two subscribing witnesses.

EBBERT J. LUND.
